(57) **CLAIM**

The ornamental design for a tire, as shown and described.

DESCRIPTION

FIG. 1 is a side perspective view of a tire showing my new design, it being understood that the tread pattern is repeated throughout the circumference of the tire, the opposite side being the same as that shown;

FIG. 2 is a front elevational view thereof, the opposite side being identical thereto;

FIG. 3 is a side elevational view of the right side thereof; FIG. 4 is a side elevational view of the left side thereof; and, FIG. 5 is an enlarged fragmentary front elevational view thereof taken along line 5-5 of FIG. 2.

The broken lines depict environmental subject matter that forms no part of the claimed design.
